[57] ABSTRACT

A writing instrument is provided with a combined decorative and functional ring or band at the juncture between the plug and the barrel of the reservoir section of the instrument. The ring or band cooperates with means on the plug to effect a locking and a sealing relationship between the plug and the barrel.

PLUG AND BARREL ASSEMBLY FOR MARKING DEVICE

BACKGROUND OF THE INVENTION

1. Field of the Invention

This invention relates to writing instruments and more particularly to a writing instrument having at least two plastic parts sealed and latched together in an effective and decorative manner.

2. Description of the Prior Art

Writing instruments and in particular writing instruments with wick-type or porous nibs have been known for some time. The numbers of different types of such instruments have been increasing so that it is becoming competitively important to provide not only a better appearing instrument, but also a less expensive and higher quality instrument. Certain manufacturers have provided a decorative metal band or ring around the barrel of the instrument generally at the juncture of the barrel with the end plug. Although the ring does enhance the appearance of the instrument, it performs no useful function, adds cost and at times contributes to a poor seal between the end plug and the barrel.

Currently two plastic parts of a writing instrument, such as the end plug and barrel, are secured together in many different ways, one such way being spinwelding wherein the two parts are spun relative to each other until the frictional heat melts and fuses the plastic material together. Another method entails the use of chemicals in the form of adhesives or material attacking agents which require long set-up time and careful control during application and setting. A third such method is mechanical wherein the parts are press-fitted together. To be effective this method requires relatively thick wall components and careful tolerance control. The last common method is the use of ultrasonics wherein a sound frequency is directed at the area to be connected for melting and fusing the plastic parts together.

Each of the four enumerated methods of attachment is limited in its applicability to the current problem because of the high costs of the equipment to effect the connection (spin-weld and ultrasonics), because of the increased costs due to slow production time (adhesives, etc.) or because of the increased material costs and resulting design limitations (mechanical connections).

SUMMARY OF THE INVENTION

The writing instrument involved in the present invention generally includes a hollow barrel for housing porous material impregnated with a marking fluid. A wick-like or porous nib projects from one end of the barrel, or from a ferrule associated with the barrel, and the inner end of the nib engages the impregnated porous material. Thus the porous material in the barrel constitutes an ink reservoir for the capillary flow of ink through the nib to the surface to be marked. The general structure of the writing instrument, except for the present invention, is as shown in the Design Patent of Walter J. DeGroft, entitled Writing Instrument, Des. Pat. 217,646, issued May 19, 1970 therefor.

The present invention is more particularly directed to a writing instrument of the above described type which has at least two plastic parts which are joined together to form the hollow reservoir or barrel thereof for the ink supply. The junction of the two parts is characterized by a decorative ring or band on one part coating with means such as a bead or beads on an interfitting portion of another part to effect a latching and sealing relationship between the two parts. The two parts are assembled by mechanically forcing the portion of one part inside the other until the means, e.g. an annular bead, on the one part becomes positioned with respect to the ring or band to latch and seal the two parts together.

BRIEF DESCRIPTION OF THE DRAWINGS

FIG. 1 is a partial perspective view of one end portion of a writing instrument incorporating the invention;

FIG. 2 is an exploded view of the parts of the end portion of the instrument of FIG. 1;

FIG. 3 is an enlarged cross-sectional view of the instrument taken along the line 3-3 of FIG. 2; and

FIG. 4 is a greatly enlarged cross-sectional view taken along the line 4-4 of FIG. 1 showing the relationship between the parts.

DESCRIPTION OF THE PREFERRED EMBODIMENT

Referring to the drawings wherein like reference numerals refer to like parts throughout the several views, a writing instrument 10 shown only in partial view is composed of an elongated, hollow barrel 12, a hollow end cap or plug 14 and a retaining ring or band 16. The illustrated embodiment is a writing instrument of the type having a wick-like or porous nib, and therefore, there is shown a quantity of absorbent material affording a reservoir element 17 in the barrel 12 and end cap 14. It is to be understood that the interior of the barrel and end plug will house the reservoir element 17 which is impregnated with marking fluid to afford a large supply source of marking fluid.

The barrel 12 is molded or otherwise formed of a plastic material such as polypropylene, and is a relatively thin-walled construction. The barrel 12 is provided with an end portion 20 having an open end 18 and an inner annular wall portion shaped to make a close mating fit with a skirt portion on the plug 14. The end of the barrel 12 opposite to the open end 18 is provided with any one of the known nibs, tips or points used for writing on a surface. The end portion 20 has exteriorly a reduced diameter recessed portion 22 extending a short distance axially of the barrel to afford an external annular seat for the band 16 as will be more fully described later. Internally the end portion 20 of the barrel has a pair of differing diameter step portions 24, 26, with the step portion 24 having both an axial dimension and a diameter larger than the axial dimension and the diameter of the step portion 26. Portion 26 has a diameter which is larger than the internal diameter of the major axial portion of the barrel 12. Between step portions 24 and 26 is a shoulder 28 and between the step portion 26 and the interior of the barrel 12 is a shoulder 30.

The end cap or plug 14 is preferably molded or otherwise formed of a resilient material such as plastic of the polypropylene type. The plug 14 has a slightly tapered outside wall 32 and an integrally formed closed end 34. The other end portion or skirt 36 of the plug 14 is at least slightly resilient and has three axially extending reduced diameter step portions 38, 40 and 42 formed in the outside wall thereof. The first step portion 38 is separated from the outside wall 32 by an axially facing shoulder 44 and has a continuous annular raised bead 46 formed approximately midway along the axial extent of said portion 38 and is generally concentric with respect to said shoulder 44. The second step portion 40 is separated from the larger diameter step portion 38 by a shoulder 48 and has a shoulder 50 separating the other end of said portion 40 from the smallest diameter step portion 42. Intermediate step portion 40 preferably has a continuous annular raised bead 52 formed approximately midway along the axial extent of said portion and lying generally concentric with respect to the shoulders 48 and 50. Sometimes in practice it has been found that bead 46 should most advantageously be slightly larger in axial and radially projecting extent as compared to the bead 52 for a reason to be more fully disclosed hereinafter.

The internal diameter of the internal step portion 24 of the barrel 12 is substantially equal to or slightly smaller than the external diameter of the external largest diameter step portion 38 of the plug 14; and the internal diameter of the internal step portion 26 of the barrel 12 is substantially equal to or slightly smaller than the external next smaller diameter step portion 40 of the plug 14. Finally, external step portion 42 of the plug 14 has a diameter substantially equal to or slightly larger than the internal diameter of the major body portion of the hollow barrel 12.

The ring 16 is a band of material, preferably metal and in most cases will have an outside surface 54 of some decorative,

contrasting color. The ring or band 16 is a shaped part being somewhat inverted L shape in cross section. The axial leg portion 56 is generally cylindrical in shape to reinforce the underlying resilient plastic portions of the barrel 12, and it is provided with an axial end 58 which is preferably tapered (as shown in FIG. 4) although it may be square (not shown). Whatever the shape of the end 58 it should substantially coincide with the shape of the axial end wall or shoulder 60 of the recess or seat 22. The horizontal leg or flange 62 of the ferrule extends radially inward from the axial leg portion 56 and has an opening with an internal diameter which is equal to or larger than the internal diameter of the step portion 24. The ring 16 is slipped over the end 18 of the barrel 12 with the leg or flange 56 resting in the recess 22 thereof. The end 58 of the leg 56 of the ring 16 rests against the wall or shoulder 60 of the barrel as the radial leg 56 of the ferrule rests against the end 18. Since the internal diameter of the leg 56 is equal to, or greater than, the internal diameter of the step portion 24, the leg 56 of the ring 16 will not extend inwardly into the barrel 12.

In assembling the end cap or plug 14 with the open end portion 20 of the barrel 12, which barrel has the ring 16 in place in the recess portion 22 as has been heretofore described, the smallest diameter step portion 42 is aligned with and inserted into the opening in the ring 16 and the open end of the barrel 12. During axial movement of the plug 14 into the barrel, it is understood that adjacent resilient plastic parts will each be mutually resiliently compressed and expanded where plug portions are slightly over-sized. The movement of the end portion 36 of the plug 14 into the end portion 20 of the barrel will be without resistance until the end of step 42 engages with the shoulder 30 between internal step portion 26 and the interior of the barrel 12. At that point pressure on the end cap or plug 14 axially of the barrel 12 will cause slight expansion of the barrel and will cause the material of the end cap or plug to resiliently compress permitting the step portion 42 to slide a short distance axially into the end portion of the barrel until the bead 52 engages with the shoulder 28.

Continued axial pressure similarly will compress the external smaller diametered intermediate step portion 40 and the bead 52, and will compress and expand adjacent portions of the inner wall of the barrel 12, until the bead 52 slides past the shoulder 28. About the time the bead 52 passes the shoulder 28 the resilient bead 46 will engage with the edge of the opening in the ring 16 and continued axial pressure will resiliently compress the raised bead 46 and largest diametered external step portion 38 until the bead 46 passes axially into the internal step portion 24. At this time the bead 46 is resiliently compressed, and adjacent inner wall portions of the barrel 12 are resiliently compressed and expanded to a lesser degree because they are reinforced by the annular leg 56 of the ring 16.

As the end plug 14 is pushed farther into the barrel, as shown in FIG. 4, the midpoint of bead 46 will preferably axially pass a small distance beyond the reinforcing annular leg 56 of band 16 and its end 58; and in this position, the nonoverlapping portion of the resiliently compressed bead 46 will radially outwardly expand into material compressing and expanding relationship with that portion of the barrel adjacent the tapered end 58 of the ring 16, while the overlapping portion of the bead 46 and ring 16 will tend to expand the barrel portion underlying the ring 16 to create an exceedingly effective latching and sealing relationship between the end plug and the barrel.

The effective latching results from the forces created by the expansion of the bead 46 beyond the end 58 of the ring, and in order to remove the end plug from the barrel, sufficient separating pressure must be created to compress the bead 46 within the confines of the barrel and its reinforcing ring. It takes considerable more separating force to part the plug from the barrel especially when you consider the small smooth difficult-to-grip surfaces of the two parts.

In addition, the partial overlap of the bead 46 with the ring 16 creates not only radial expansive forces in the ring encased portion of the step 24 of the barrel but also it creates axial compressive and expansive forces between the area of the bead indenting into the plastic step 24 and the horizontal leg portion or flange 62 of the ring 16 tending to increase the latching effect between the end plug and the barrel.

The positive sealing effect between the end plug and the barrel is accomplished in a threefold manner herein. First, the seal created by the expansion of the beads 46 and 52 into the respective stepped portions 24 and 26 of the barrel; and, second, the seal created by the partial overlap of the bead 46 with the end 58 of the leg 56 of the ring 16 creating the relative compressive and expansive sealing effects between the barrel step portion 24 within the ring leg 56 and flange 62 and the end plug. The third seal is created by the substantial coincidence between the diameters of the barrel and the smallest external diameter step portion 42. That is, the diameters of the portion 42 and barrel are uniform throughout their overlapping axial length so as to avoid openings of a capillary nature. Because of the effective seal, the ink impregnated reservoir can be expanded to include the volume of the hollow plug, as shown in FIG. 3 without fear of leakage at the juncture of the plug and barrel.

The band or ring 16 serves not only the purpose of being decorative but also restricts the outward expansion of the thin walled end of the barrel. Plastic is known to fatigue and to cold-flow when deformed over a period of time, and it may crack when expanded beyond the limits of its resiliency. The reinforcing ring 16 of the present invention aids in the solutions obviating all of these problems. Furthermore, by using the ring as a reinforcement, it is possible to reduce the thickness of the barrel walls of the writing instrument thereby increasing the volume of the writing fluid in the writing instrument and the usable life and value of the instrument. Reducing the wall thickness also reduces the amount of material needed to mold the instrument thereby reducing the cost of making the device. The thinner walls require less cooling time in the molding cycle and therefore the speed of manufacturing is increased further reducing the cost of making the device. Finally, by having an effective seal and latching at the juncture of the plug and barrel, the open end of the barrel adjacent the plug can be used to conveniently place the absorbent material of the reservoir into the barrel during one of the steps of assembly in manufacturing.

The invention clearly accomplishes the prime objectives of providing an improved instrument which is substantially trouble free from a leaking standpoint while at the same time making use of one of the simplest methods of assembly, namely, mechanical assembly. In addition to the improved results created by the invention, a writing instrument is produced which is cheaper in material and manufacturing costs, and which provides a larger internal reservoir and therefore a longer writing capability.

I claim:

1. In a writing instrument of the type having a reservoir for marking fluid, a plug and barrel assembly, and a writing means on said barrel assembly, comprising: an elongated hollow barrel having an inner chamber to house the reservoir and being provided with an annular open end portion of resilient material, said barrel having the writing means mounted on the end opposite said open end portion, the end portion having an annular inner wall portion; a plug member closed at one end and having an annular resilient skirt positioned within the open end portion of the barrel and shaped to make a close mating fit within said annular inner wall portion, said skirt having an annular outwardly extending continuous bead shaped similarly to the contour of the skirt and making a continuously contacting resilient sealing fit against said annular inner wall portion; and an annular retaining ring positioned about the annular open end portion of the barrel to restrain expansion of the underlying inner wall portion, said ring being positioned between the outwardly extending bead and the open end of the barrel

to latch the bead of the plug member in sealing relation against the inner wall portion of the barrel.

2. A plug and barrel assembly as specified in claim 1 in which the bead is positioned longitudinally inwardly of the open end of the barrel beyond the position of the retaining ring and in partially overlapping relation with respect to said ring.

3. A plug and barrel assembly as specified in claim 1, in which the skirt portion is provided with a cylindrical reduced diameter step portion in its outer surface, and the inner wall portion is cylindrically shaped and of substantially the same diameter as said step portion, the outwardly extending bead being circular and being located intermediate the ends of said cylindrical reduced diameter step portion.

4. A plug and barrel assembly as specified in claim 1 in which the inner wall portion of the barrel is provided with interior plural different diameter step portions, and the annular skirt of the plug is provided exteriorly with corresponding plural different diameter step portions, the corresponding step portions being shaped to make a close mating fit of the skirt within the open end portion of the barrel.

5. A plug and barrel assembly as specified in claim 4 wherein said continuous annular bead is formed on the exterior of one of said step portions of said plug for sealing with a corresponding interior step portion in the inner wall of said barrel.

6. A plug and barrel assembly as specified in claim 1 wherein the retaining ring has a cylindrical portion nested in a recess in the exterior surface of the open end portion of the barrel and an integrally formed, radially inwardly directed flange portion overlying the end edge of said open end portion of the barrel whereby the latching force created by said bead compresses the material of the end of the barrel generally axially against said flange of the ring and generally radially against the cylindrical portion of said ring.

7. In a plug and barrel assembly as specified in claim 1 wherein the material of the barrel and plug is plastic and the walls of said barrel are relatively thin.

8. A writing instrument having a barrel with one open end and with a writing means projecting from the other end, a plug assembled with the open end of said barrel, and means for latching and sealing said plug in the open end of said barrel, said means comprising plural different diameter step portions on the exterior of the open end portion of said plug, outwardly extending continuous beads formed on at least two step portions on said plug, plural different diameter step portions formed on the interior of the open end portion of said barrel, the diameters of the corresponding step portions on the plug and in the barrel being substantially equal, an annular retaining ring having a cylindrical portion encircling the exterior open end portion of said barrel, the bead on the largest diameter step portion of the plug being positioned in partially overlapping relationship with the remote end of the cylindrical portion of the ring thereby compressing the corresponding step portion of the barrel into a latching end sealing relationship with said plug, and a second seal being effected between the barrel and the plug by said bead on the next largest diameter step portion of the plug indenting into the material of the corresponding step portion of the barrel whereby the barrel and plug are securely latched and sealed together.

9. A writing instrument as claimed in claim 8 wherein said ring has a radially inwardly directed flange portion overlying the end of the barrel whereby the latching and sealing created by the bead on the largest diameter step portion is effected in

65

the material of the barrel by the axial and radial compressive forces created between the flange and cylindrical portions of the retaining ring and said last named bead.

10. A writing instrument as claimed in claim 8 wherein the diameter of one step portion of said plug coincides throughout its length with a corresponding substantially equal in diameter internal portion of said barrel whereby sealing against capillary leaking therebetween is effected.

11. A writing instrument as claimed in claim 8 wherein the material of the barrel and plug is a plastic material and the material of said retaining ring is a metal material.

12. In a writing instrument having an elongated, hollow barrel made of plastic material and with one open end and with a porous writing nib projecting from the other end, a cap frictionally and removably attached to said barrel in covering relationship to said writing nib, and a plug made of plastic material and having one end closed and having the other end open, said open end of the plug being assembled with the open end of said barrel, in combination, means for latching and sealing said open end of said plug in the open end of said barrel, said means comprising plural different diameter step portions on the exterior of the open end of said plug, an outwardly extending continuous bead formed on the largest and next largest diameter step portions of said plug, plural different diameter step portions formed on the interior of the open end portion of said barrel, the diameters and axial lengths of the corresponding step portions on the plug and in the barrel being substantially equal, an annular retaining ring having a cylindrical portion and an inwardly directed flange portion, said cylindrical portion of said ferrule nesting in a recess in the exterior end portion of said barrel with said flange portion capping the end edge of said barrel, the bead on the largest diameter step portion of the plug being positioned in partially overlapping relationship with the remote end of the cylindrical portion of the ferrule thereby compressing the corresponding step portion of the barrel into a latching and sealing relationship with said plug, and a second seal being effected between the barrel and the plug by said bead on the next largest diameter exterior step portion of the plug indenting into the material of the corresponding interior step portion of the barrel whereby the barrel and plug are securely latched and sealed together.

13. In a writing instrument of the type having a reservoir for marking fluid, a plug and barrel assembly, and a writing means on said barrel assembly comprising: an elongated hollow barrel member having an inner chamber to house the reservoir and being provided with an annular open end portion of resilient material, said barrel having the writing means mounted on the end opposite said open end portion, a plug member closed at one end and having an annular open end portion coaxing with the annular open end portion of the barrel member to make a close mating fit therewith, the open end portion of one of said members having a skirt with an annular outwardly extending continuous bead shaped similarly to the contour of the skirt, the open end portion of the other of said members having an annular inner wall portion such that said continuous bead makes a continuously contacting resilient sealing fit thereagainst; and an annular retaining ring positioned about the annular open end portion of said other member to restrain expansion of the underlying inner wall portion, said ring being positioned between the outwardly extending bead and the open end of said other member to latch the bead of the one member in sealing relation against the inner wall portion of the other member.
